UNITED STATES PATENT OFFICE.

CARL H. AU, OF WASHINGTON, DISTRICT OF COLUMBIA.

FLEXIBLE POWER-TRANSMITTING DEVICE.

1,331,311.

Specification of Letters Patent.

Patented Feb. 17, 1920.

Application filed May 16, 1919. Serial No. 297,486.

To all whom it may concern:

Be it known that I, CARL H. AU, a citizen of the United States of America, and a resident of Washington, District of Columbia, have invented a new and useful Improvement 5 in Flexible Power-Transmitting Devices, which invention is fully set forth in the following specification.

The present invention relates to improvements 10 in flexible power-transmitting devices, and more particularly to devices of the above class suitable for applying power to release devices such as photographic shutters, or for operating automobile horns or other devices 15 to which power is applied through a flexible shaft.

Heretofore flexible power-transmitting devices have been constructed with an inner inextensible cable and an outer incompressible 20 tube. The power in all such cases has been transmitted through the movement of the inner cable by either a thrust which tends to buckle the cable inside its tubular casing stretching the latter and interfering with 25 the usefulness of the transmission device, or by a manual pull on the inner cable which limits the field of usefulness of the device and practically excludes its employment on cameras used in aerial photography at high 30 elevations where the temperature is low, and tractible hand manipulation difficult or impossible.

My invention overcomes the above objections and resides in providing an inner inextensible tension member such as a wire cable 35 having means at one or both ends for attachment, and an outer flexible incompressible member such as a tube formed of a helical metal ribbon movable over the tension member 40 and provided with means at one end for applying its power beyond one of the attaching means of the tension member. This latter means preferably consists of a plunger working in a tubular casing and is yieldingly held between the end of the power 45 member and the tubular casing to which one end of the tension member is secured. By reason of the above construction wherein the inner element is a tension member, and the 50 outer element is an integral compression member, there is no lost motion between the parts and the resultant effect is a thrust applied beyond the point of attachment of the tension member.

55 In order that my invention may more

readily be understood, reference is had to the accompanying drawings which illustrate by way of example one constructional form thereof and are intended to assist the description of the invention but not to limit 60 its scope.

Figure 1 is a side view of a flexible power-transmitting device constructed in accordance with my invention, a portion of the flexible transmitting section having been cut 65 out.

Fig. 2 is a central longitudinal sectional view of the device taken on the line 2—2 of Fig. 1 showing the position of parts when in normal position of rest.

Fig. 3 is a similar sectional view of Fig. 2 showing the parts in operative position.

Figs. 4, 5 and 6 are detail views.

Fig. 7 is a general view showing the application of my improvement to the operation 75 of a shutter in an aerial camera.

Figs. 8 and 9 are enlarged detail views.

Referring more particularly to Figs. 1, 2 and 3 of the drawings, 1 is a cylindrical casing provided with means, such as a 80 threaded neck portion 2, for attachment to any suitable abutment. Within casing 1 plays a hollow plunger 3 provided with a shoulder portion 4 adapted to retain a spring 5 normally tending to restrain the plunger 85 from outward movement. Fitting the interior of plunger 3 is a head 6 which is made fast to casing 1 by means of a pin 7 which passes through slots 8 formed in the walls of the plunger 3. To head 6 is secured one end 90 of a flexible inextensible tension member such as a wire cable 9 and to plunger 3 is secured one end of an incompressible power member, such as a helically-wound metal tube 10.

95 For the purpose of anchoring the opposite end of cable 9, when desired, any suitable means may be provided. Illustrative of one such means, I have shown a head-piece 11 to which the outer end of the cable 9 is secured 100 by solder. This head is centrally held within an annular plate 12 by means of a bar 13 fast to the latter. In Figs. 7 and 8 this plate is shown mounted on a bracket 13 secured to the framing of an airplane. The 105 power-receiving end of the flexible power-member 10 is secured to a tube 15 adapted to receive the head 11 and is provided with opposite slots 16 which receive the bar 13 and permit free play of the tube over the 110

head 11 and bar 13. The outer end of the tube is provided with a knob 17 and secured in position by a pin 18.

Assume that the device is to be used for 5 operating the shutter-release means of a camera, and that the latter is to be mounted for aerial photography on an airplane as shown in Fig. 7. The parts of the device are assembled as shown in Fig. 2. The cylinder 1 is made fast to a part of the camera by screwing the neck 2 into a suitable support such as a threaded socket 19 (Fig. 7) fast to the camera wall. The hand-operating end of the transmission is supported on 10 the framing of the airplane in easy reach of the photographic observer. When the device is thus supported, the ends 1 and 12 (Figs. 9 and 8) of the tension member 9 are anchored to stationary members 19 and 15 14 and the power-transmitting member 10 is adapted to be moved over the cable, the ends of the latter being supported in the plunger 3 and tube 15 respectively.

By reason of this construction the inner 20 wire cable becomes a stationary tension element and the outer incompressible movable element 10 becomes the power-transmitting element or thrust element. A direct push by the hand or a blow of the fist on the 25 knob 17 is transmitted through the flexible outer incompressible thrust member 10 to the plunger 3 which is forced out of its casing against the tension spring 5. Spring 30 5 returns the parts to their original positions.

It will be observed from the above that 35 the outer flexible element moves over the inner stationary element of the flexible transmission, thereby obviating the endwise compression of a flexible element inside a 40 tube and thereby preventing buckling and obstruction by the power element and further that the thrust on the outer flexible element is through an integral element and 45 is transmitted beyond the anchored end of the tension element and in axial alignment with the tension element, thereby retaining the advantages of axial alignment and also dispensing with levers and their attendant 50 lost motion.

What is claimed is:

1. In a flexible power-transmitting device, 55 the combination of a flexible inextensible tension member provided with end abutments, a tubular, flexible, incompressible, power-transmitting member movable over

said tension member and provided at one end with a plunger for applying an outward thrust beyond one end of said tension member, and yielding means normally restraining movement of said plunger. 60

2. In a flexible power-transmitting device, the combination of a flexible, inextensible tension member and a tubular flexible, incompressible power-transmitting member 65 movable over said tension member, means for anchoring one end of said tension member, and a power-delivering element yieldingly held between the end of said tubular power-transmitting member and said anchoring means, for applying power beyond 70 the anchored end of said cable.

3. In a flexible power-transmitting device, the combination of a flexible inextensible tension member and a tubular, flexible, incompressible, power-transmitting member movable over said tension member and provided with a plunger for applying power beyond the end of said tension member, a tubular casing to which one end of said 75 tension member is anchored and in which said plunger works, and yielding means normally restraining the longitudinal movement of said flexible power member.

4. In a flexible power-transmitting device, 80 the combination of a flexible, inextensible tension member and a tubular, flexible, incompressible power-transmitting member movable over said tension member, a tubular casing to which one end of said tension 90 member is anchored, a power-delivering plunger working in said casing and yieldingly held between one end of said flexible power member and said casing for delivering power beyond the anchoring point of 95 said tension member.

5. In a flexible power-transmitting device, the combination of a flexible, inextensible tension member and a tubular, flexible, incompressible power-transmitting member 100 movable over said tension member and provided with a plunger for applying power beyond the end of said tension member, means for anchoring one end of said tension member, yielding means normally restraining the longitudinal movement of said flexible power member and a manual thrust member secured to one end of said tubular, 105 flexible power member.

In testimony whereof I have signed this 110 specification.

CARL H. AU.
